VARIABLE-SPEED DRIVE CONTROL FOR
SPINNING FRAMESJohn S. Michie and Paul B. Reeves, Columbus,
Ind., assignors to Reeves Pulley Company, Co-
lumbus, Ind., a corporation of Indiana

Application November 12, 1949, Serial No. 126,862

3 Claims. (Cl. 74—230.17)

1

The present invention relates to variable speed drive control assemblies, primarily for transmitting power, at stepless variable speed ratios, to spinning frames, or like machines; and the primary object of the invention is to provide an assembly so constructed, designed and arranged as to be associative, readily, with any one of a plurality of conventional spinning frames, or the like, in a convenient manner which shall be conservative of space. A further object of the invention is to provide an assembly of the character suggested in which the adjusting means for the assembly shall not project into aisleways, where it might accidentally be shifted by passing persons or objects, but shall be so located that, while it is readily accessible for actuation by an authorized operator, it will be completely protected against unauthorized, accidental shifting. Further objects of the invention will appear as the description proceeds.

To the accomplishment of the above and related objects, our invention may be embodied in the form illustrated in the accompanying drawings, attention being called to the fact, however, that the drawings are illustrative only, and that change may be made in the specific construction illustrated and described, so long as the scope of the appended claims is not violated.

Fig. 1 is an end elevation of an assembly constructed in accordance with our invention;

Fig. 2 is a side elevation, parts being shown in section, and showing our assembly in operative association with a driving motor and a machine to be driven;

Fig. 3 is a perspective view of the assembly of the present invention;

Fig. 4 is an enlarged perspective of the trunnion element preferably used in the preferred embodiment of our invention; and

Fig. 5 is a longitudinal section through the positively actuated pulley incorporated in the illustrated embodiment of our invention.

Referring more particularly to the drawings, it will be seen that we have illustrated, in dotted lines, an electric motor 10 and the main shaft 11 of a machine 12 which may be a spinning frame. In accordance with standard practice, the shaft 11 projects a substantial distance from the end of the frame, being supported, in this instance, by an outboard bearing 11'.

In spinning mills, it is customary to arrange the frames in series and ranks, with relatively narrow aisles between adjacent frames, and for that reason, it is undesirable to arrange driving means in such a fashion as to project substan-

2

tially beyond the free end of the shaft 11. According to our present invention, a driving motor 10 for each frame may be tucked under the projection of the shaft 11, with an assembly for providing variable speed ratios between the motor and the shaft likewise located substantially within the region of projection of said shaft.

Specifically, a bed plate 13 will be located with one end 14 closely adjacent the end of the spinning frame 12, said plate lying substantially within the region of projection of the shaft 11. Adjacent said bed plate end 15, a standard 16 is suitably secured to said bed plate on one side of the median longitudinal line of said bed plate, and preferably closely adjacent one side edge 17 of said bed plate. A base element 18 is similarly secured to the bed plate 13 near the opposite edge 19 thereof, and close to the end 15 thereof. Thus, it will be clear that the standard 16 and the base 18 are located on opposite sides of the median longitudinal line of the plate 13.

At its upper end, the standard 16 is provided with a bearing enlargement 20 in which is journaled a screw 21. That end 22 of the screw which projects toward the bed plate end 15 is cylindrical, as shown, while the opposite end 23 of said screw, projecting from the bearing enlargement 20 in the direction of the bed plate end 14, is polygonal for a reason which will appear. Said enlarged, polygonal head 23 engages one end of the bearing enlargement 20, while a set collar 24, adjustably fixed to the screw 21, engages the opposite end of said enlargement, whereby the screw 21, while it is free for rotation about its axis, is held against axial movement relative to the standard 16.

A trunnion element 25 is provided with a threaded bore 26 and is threadedly mounted on the screw 21. Oppositely extending, coaxial projections 27 and 28 provide spaced, aligned trunnion surfaces on said element 25, for a purpose which will appear.

The base 18 is provided with a bearing enlargement 29 in which is received a pin 30 having a preferably threaded portion projecting from said base toward the end 15 of the bed plate 13. A trunnion element 25', having projections 27' and 28', in all respects similar to the projections 27 and 28, is mounted on said projecting portion of the pin 30. It will be noted that the pin 30 and the screw 21, both parallel with the plane of the upper surface of the bed plate 13, are differently spaced therefrom; so that the plane common to the axes of said pin and said screw is inclined to the bed plate, and traverses the vertical plane in-

cluding said longitudinal median line of the bed plate. It is intended that the motor 10 shall be set on the bed plate, between the standard 16 and base 18 and the spinning frame 12, with the axis of its spindle located in the line of intersection between said vertical plane including the longitudinal median line of the bed plate and the plane common to the axes of the screw 21 and pin 30.

A yoke, indicated generally by the reference numeral 31, is preferably formed of two mating sections 32 and 33 joined by screws 34 and 35, or other equivalent fastening means. The section 32 is provided at one end with a pair of furcations 36 straddling or embracing the trunnion-surface projection 27 of the trunnion element 25; and with a pair of furcations 37 similarly straddling the projection 27' of the trunnion element 25'. Similarly, the yoke section 33 is provided with furcations 38 straddling the projection 28, and with furcations 39 straddling the projection 28'. Intermediate its ends, the yoke section 32 is provided with means 40, and the yoke section 33 is similarly provided with means 41, establishing a pivotal connection between the yoke and a bearing 42.

An expansible V-pulley is indicated generally by the reference numeral 43, and comprises a coned disc 44 having an axially-extending hub 45 projecting in the direction in which its coned surface faces, said hub being hollow, at least at its rear end, as at 46, and being provided with a set screw 47, or other suitable means, for securing the disc 44 to the motor spindle 48 upon which said hub is adapted to be sleeved. Said pulley further comprises a mating coned disc 49 telescopically slidably mounted on the hub 45 and provided with a rearwardly axially projecting hub 50, a key 51 providing a driving connection between the hubs 45 and 50. A two-way thrust bearing 42 is sleeved on the hub 50, and is confined thereon between an outwardly-facing shoulder 50' and a snap ring 50'', whereby axial movement of the bearing 42 in either direction will be transmitted to the disc 44.

Our control includes also a resiliently expansible V-pulley indicated generally by the reference numeral 52 and comprising a coned disc 53 having a hub 54 axially projecting in the direction in which the coned surface of said disc faces, said hub being hollow, at least at its free end, as at 55, so that it is adapted to be sleeved on the spinning frame shaft 11; and said hub is provided with fastening means, such as the set screw 54' for securing the same to said shaft. A mating coned disc 56, having an axially elongated hub 57 projecting away from its coned surface, is telescopically received on the hub 54. A coiled spring, retained in a suitable housing, cooperates with the hubs 54 and 57 to press the disc 56 resiliently toward the disc 53. An edge-active belt 59 is trained over the pulleys 43 and 52 to provide a driving connection therebetween.

Preferably, a bar 60 is secured to the upper end of the standard 16 and projects therefrom in parallelism with the screw 21, said bar carrying, on its upper surface, a graduated scale plate 61.

It will be clear that, when the motor 10 is energized, it will drive the shaft 11, through the control assembly above described, at a speed ratio depending upon the current effective pitch diameters of the pulleys 43 and 52. A ratchet wrench may be applied to the polygonal head 23 of the screw 21 to rotate the same to adjust the position of the trunnion element 25. Rotation of the

screw in one direction will shift the trunnion element 25 toward the right as viewed in Fig. 2, and the upper end of the yoke 31 will be carried with the element 25 because of the engagement of the furcations 36 and 38 with the trunnion projections 27 and 28. Thus, the yoke 31 will be caused to swing about the axis of the projections 27 and 28' of the trunnion element 25', in a clockwise direction as viewed in Fig. 2, moving the bearing 42 toward the right to force the disc 49 toward the disc 44. Thereby, the belt 59 will be squeezed radially outwardly between the mating coned surfaces of said discs, and will be pulled radially inwardly between the mating faces of the discs 53 and 56, thereby causing the disc 56 to be moved toward the right, as viewed in Fig. 2, against the tendency of the spring 58. Thus, the effective diameter of the pulley 43 will be increased, the effective diameter of the pulley 52 will be decreased, and the speed of the pulley 52, and therefore of the shaft 11, will be increased. As the trunnion element 25 is so moved, its position relative to the scale 61 will be changed, and said scale may be calibrated so that the position of the element 25 relative thereto may be read in, for instance, revolutions per minute of the shaft 11.

If the screw 21 is rotated in the opposite direction, of course the block 25 will be moved toward the left, as viewed in Fig. 2, thus shifting the bearing 42 and the disc 49 toward the left to relieve the pressure exerted by the discs 44 and 49 against the belt 59. The spring 58 will concurrently shift the disc 56 toward the disc 53, squeezing the belt 59 radially outwardly between said discs, and pulling it more deeply between the discs 44 and 49, thereby reducing the speed of the shaft 11.

The canting or inclination of the yoke 32 permits the arrangement of the control assembly in various positions of transaxial adjustment relative to the shaft 11. If desired, one or both of the elements 16 and 18 may be laterally adjustably mounted on the bed plate 13 to vary the angle of inclination of said yoke, thereby varying the elevation of the point of intersection between the plane common to the screw 21 and the pin 30, and the vertical plane including the median longitudinal line of the bed plate. The particular type of connection between the yoke ends and the trunnion elements 25 and 25' will permit such adjustment, through a limited range.

While we presently believe the particular construction of expansible V-pulleys herein disclosed to be optimum, those structural details are not essential to our invention, so long as one disc of one V-pulley is under the control of the yoke 31, and the discs of the cooperating V-pulley are resiliently urged toward each other.

We claim as our invention:

1. A variable-speed drive control assembly for spinning frames or the like, comprising a bed plate adapted to be mounted with one end adjacent the drive end of a spinning frame, a standard fixedly supported adjacent the other end of said plate at one side of a median line thereof, and a base fixedly supported adjacent said other end of said plate at the other side of said line, said plate being adapted to support an electric motor adjacent said one end of said plate with its spindle projecting toward said other plate end and located substantially with its axis in the vertical plane including said median line, a pin carried by said base with its axis substantially parallel with said median line, a trunnion block

mounted on said pin and provided with aligned, spaced trunnion surfaces transaxially related to said pin, a yoke provided at one end with furcations straddling said trunnion surfaces, a screw journalled in said standard upon an axis substantially parallel with said pin axis, a second trunnion block threadedly mounted on said screw and provided with aligned, spaced trunnion surfaces transaxially related to said screw, said yoke being provided at its opposite end with furcations straddling said trunnion surfaces of said second trunnion block, bearing means, said yoke, intermediate its ends, being pivotally engaged with said bearing means upon an axis parallel with said trunnion surface axes, an expansible V-pulley comprising a coned disc having a hollow hub axially elongated in the direction in which its coned surface faces, said hub being adapted to be sleeved on the spindle of such a motor, and a mating coned disc slidably telescoped on said hub and having an axially elongated hub retreating from its coned surface, said bearing means being sleeved on said last-named hub, and said last-named hub being provided with a shoulder facing the free end of said hub and engaged by said bearing means, a resiliently-expansible V-pulley comprising a coned disc having a hollow hub axially elongated in the direction in which its coned surface faces and adapted to be sleeved on, and

supported by, the main shaft of such spinning frame, a mating coned disc slidably telescoped on said hub, and spring means cooperating with said discs to urge the same toward each other, and an edge-active belt for providing a driving connection between said pulleys.

5. The assembly of claim 1 in which said pin axis and said screw axis are parallel with said bed plate, but are located at substantially different distances from said plate.

10. The assembly of claim 1 in which that end of said screw adjacent the position of such a motor is polygonal to facilitate rotation of said screw, the opposite end thereof being cylindrical.
